E. E. TIBBETS,
VALVE SPRING LIFTER.

APPLICATION FILED JULY 22, 1919.

1,384,648.

Patented July 12, 1921.

UNITED STATES PATENT OFFICE.

EARL E. TIBBETS, OF HEBRON, NEBRASKA.

VALVE-SPRING LIFTER.

1,384,648.

Specification of Letters Patent. Patented July 12, 1921.

Application filed July 22, 1919. Serial No. 312,491.

To all whom it may concern:

Be it known that I, EARL E. TIBBETS, a citizen of the United States, residing at Hebron, in the county of Thayer and State 5 of Nebraska, have invented certain new and useful Improvements in Valve-Spring Lifters; and I do hereby declare the following to be a full, clear, and exact description of the invention, such as will enable others skilled 10 in the art to which it appertains to make and use the same.

This invention relates to new and useful improvements in valve spring lifters especially adapted for use on internal combustion engines of the type employed in Ford automobiles and has for one of its objects the provision of a device of the above stated character wherein the spring of a puppet valve used in the above named engine can 20 be lifted and supported in a raised position by said device so that both hands of the operator or mechanic can be used to remove the locking pin of the valve.

Another object of this invention is the 25 provision of a valve spring lifter of the above stated character which shall be simple, durable and efficient, and which may be manufactured and sold at a comparatively low cost.

With these and other objects in view as 30 will become more apparent as the description proceeds, the invention consists in certain novel features of construction, combination, and arrangement of parts as will be 35 hereinafter more fully described and claimed.

For a complete understanding of my invention reference is to be had to the following description and accompanying drawing in which,

40 Figure 1 is a fragmentary sectional view of an engine illustrating a valve spring lifter applied thereto and constructed in accordance with my invention,

Fig. 2 is a side elevation of the valve 45 spring lifter,

Fig. 3 is a fragmentary plan view of one of the arms of the lifter.

Referring in detail to the drawing, the 50 numeral 1 indicates an engine having the usual puppet valves 2 held in closed position by valve springs 3. The engine 1 is provided with the usual removable head 4 which can be removed to clean the engine and expose the valves and valve seats. The 55 valves are held closed by springs which

seat against pins 6 in the valve stems. In order to remove one of the valves 2 from the engine it is necessary that the pin 6 be removed in order to do this, the spring has to be compressed or raised upwardly and 60 this is accomplished with my tool.

A horizontal arm 7 is adapted to be associated with the engine 1 and one end thereof engages or rests on the head of the valve to be removed, while the other end of the 65 arm 7 has formed thereon an upwardly and outwardly extending handle 8 to which is connected a ring 9. The handle 8 as will be noted by the drawing is disposed a short distance from the side of the engine. A 70 handle 10 is pivoted to the arm 7 at a point adjacent the formation of the handle 8 to said arm and the arm 10 extends above and below the arm 7 and has formed upon its lower end a horizontally disposed arm 11 75 which extends parallel with the arm 7 and in a plane below the same. The free end of the arm 11 is enlarged as illustrated at 12 and bifurcated to form a slot 13 that opens outwardly through the edge of said enlarged 80 portion so as to receive the lower end of the valve stem. The top face of the enlarged portion 12 is concaved as illustrated at 14 to form a seat adapted to receive the washer 15 on the valve stem and which is interposed between the key or pin and the lower 85 end of the valve spring so that on moving the handle 10 in the direction of the handle 8 the spring will be compressed and also the washer 15 raised upwardly on the valve 90 stem, freeing or relieving the pressure on the pin or key so that the same can be readily removed from the valve stem. When the spring has been compressed and the washer raised the handle 10 is in close proximity to the handle 8 and the ring 9 is swung over the handle 10 to lock the handles 95 against movement in relation to each other. Owing to the fact that the arm 7 engages the valve head, said valve is held against 100 upward movement. After the spring has been compressed and the handles locked together the tool may then be released and will support itself in such a position with the spring compressed so that the mechanic 105 is free to use both of his hands for other purposes such as removing the pin or key from the valve stem.

While I have shown and described the preferred embodiment of my invention, it 110

will be understood that minor changes in construction, combination, and arrangement of parts may be made without departing from the spirit and scope of the invention 5 as claimed.

Having thus described my invention, what I claim is:-

A valve spring lifter comprising a horizontally disposed arm adapted to rest on 10 the head of a valve, an outwardly and upwardly inclined handle formed on said arm, a second handle of a greater length than the first handle pivoted to the arm adjacent its formation onto the first handle, said second 15 handle terminating in a plane substantially with the free end of the first handle, a second horizontal arm formed on the lower

end of the second handle and extending at right angles to the second handle and in a plane below the first arm, an enlarged portion formed on the end of the second arm and having a slot opening outwardly through one edge thereof and having a concaved recess in its upper face, and a ring pivoted to the first handle and adapted to 20 engage over the second handle when said handles are moved in parallelism.

In testimony whereof I affix my signature in presence of two witnesses.

EARL E. TIBBETS.
